UNITED STATES PATENT OFFICE.

FRANK GUAY, OF WHITEFISH, MONTANA.

ROTARY WASHING MACHINE.

Application filed March 8, 1922. Serial No. 542,079.

To all whom it may concern:

Be it known that I, FRANK GUAY, a citizen of the United States, residing at Whitefish, in the county of Flathead and State 5 of Montana, have invented certain new and useful Improvements in Rotary Washing Machines, of which the following is a specification.

My invention relates to an improvement 10 in rotary washing machines.

It has two main objects; one is to prevent the machine from turning when the door is open, and the other to prevent articles of laundry from falling between the 15 stationary and rotary cylinder when the door is open.

In the accompanying drawings:

Fig. 1 is a transverse vertical section;

Fig. 2 is a fragmentary detail in trans- 20 verse section on an enlarged scale;

Fig. 3 is a view in perspective of the guard;

Fig. 4 is a transverse section showing the trip and clutch mechanism;

Fig. 5 is a longitudinal section on line 25 5-5 of Fig. 4;

Fig. 6 is a transverse section on line 6-6 of Fig. 5, looking toward the right.

A, is the outer cylinder forming the shell 30 of the machine, with the opening 1 in the upper side; and 2, indicates the rotary cylinder having the ribs 3 and 4 at intervals, as shown in Fig. 1. A door 5 is hinged to one side of the opening in the rotary cylinder, and, when open, the articles to be 35 washed are passed through this door-way. The rib 4 is grooved, and a guard 6 is slidably placed in a groove 7 therein, it being actuated by a spring 8 which tends to force 40 it out. The purpose of this guard is to close the space between the two cylinders, as shown in Fig. 1, when the articles are passed through the door-way, that is to say when the door 5 is open. It will be seen 45 that when the door is open, the spring 8 forces it out, and it bridges the space between the two cylinders.

Upstanding lugs 9 on the guards are in 50 position to be engaged by the edge of the door 5, when it is closed, to force the guard in and out of the way, the spring automatically projecting the guard the moment the door 5 is open.

As a means for preventing the cylinder 55 from starting when the door is open, which

often happens to the injury of the machine or the laundryman operating it, an automatic trip is provided as shown in Figs. 1, 3, and 4. The trip-lever 10 is pivoted at 11 to the end of the inner cylinder or 60 drum 2, and its free end is in the path of the door as shown in dotted lines when the door is open, the door forcing it in when closed, as shown in the full lines.

A spring-actuated rod 12 is pivotally connected with the trip lever 10 at 13, and this rod carries a wedge 14 which is forced endwise against the hub 15 of the clutches 16, which latter frictionally engage the rim of the pulley 17. A spring 18 in the shaft 65 19 upon which the pulley 17 is mounted normally forces the hub 15 inwardly, unclutching the pulley 17 when the door 5 of the cylinder 2 is open. The reverse action, of course, takes place when the door 5 is 70 closed, in other words causing the clutches 16 to engage the pulley 17 to drive the cylinder. In this way, it is impossible for the cylinder to rotate while the door is open.

Thus two improved means are provided— 80 one a means for preventing goods from dropping between the two cylinders when the door is open; and the other to prevent accident by reason of the cylinder starting to rotate when the door is open.

I claim:

1. A washing-machine including an outer and an inner cylinder spaced apart, a door for the inner cylinder, and a spring-actuated slidably mounted guard which automatically projects itself to cover the space between the two cylinders at the edge of the door-way when the door is open.

2. A washing-machine including an outer and inner cylinder spaced apart, a door 95 for the inner cylinder, and a guard which automatically projects itself to cover the space between the two cylinders at the edge of the door-way when the door is open, and means connected with the guard in the path 100 of the door to cause the guard to be pushed aside or out of the way when the door is closed.

3. The combination of a stationary shell, a rotary cylinder having a movable door 105 and ribs on the inside of the cylinder, one of which ribs is grooved, a guard slidably mounted in the hollow rib and extending through the outer side thereof, a spring in said rib for automatically projecting the 110

guard to cover the space between the shell and cylinder when said door is open, said guard projecting into the path of the door so that, when the latter is closed, it forces 5 said guard into said hollow rib.

4. The combination with an outer shell, and a rotary cylinder therein having an actuating shaft, a door hinged to the cylinder for closing the latter, and a clutch 10 mechanism on said shaft actuated by the door to disconnect said mechanism from said shaft to prevent the rotation of the cylinder while the door is open and for lock-

ing it to its actuating shaft when the door is closed.

5. The combination of inner and outer cylinders, the inner cylinder being a rotary cylinder, a door hinged to the inner cylinder for opening and closing the latter, a shaft for turning the cylinder, a pulley 20 thereon, a clutch for fastening the pulley to the shaft, and a clutch-lever, in position to be actuated by the door as it is closed.

In testimony whereof I affix my signature.

FRANK GUAY.
